UNITED STATES PATENT OFFICE.

EDWARD P. NOYES, OF WINCHESTER, MASSACHUSETTS, ASSIGNOR TO CHARLES F. BROWN,
TRUSTEE, OF READING, MASSACHUSETTS.

DIFFERENTIAL LIQUID-LEVEL APPARATUS.

No. 909,206.

Specification of Letters Patent. Patented Jan. 12, 1909.

Application filed August 30, 1907. Serial No. 390,726.

To all whom it may concern:

Be it known that I, EDWARD P. NOYES, a citizen of the United States, residing at Winchester, in the county of Middlesex and State of Massachusetts, have invented certain new and useful Improvements in Differential Liquid-Level Apparatus, of which the following is a specification.

This invention relates to boiler feeders, traps, etc., of the differential-septum type described in Reeve and Noyes patent No. 824,143, the operation of which depends upon the principle of releasing a small quantity of the steam or other pressure fluid from that one of the two differential-pressure chambers which is closed off from the boiler or other pressure vessel by the rise of the liquid above normal level. The release-valve in controllers of this nature requires to be adjusted to a very small opening and heretofore has been somewhat subject to clogging which in practice was relieved by occasionally opening the valve by hand to blow out the sediment.

It is the principal object of the present invention to render the relief-valve automatic in operation and to secure greater reliability of performance as well as less necessity of attendance. This object is accomplished by making the valve subject to thermostatic control and I also make it adjustable by hand with the further object of enabling the controller at times to operate normally on the condensation principle, the pressure being reduced in the variable-pressure chamber at times of super-normal water level by condensation of the steam in said chamber. The valve then only opens when the thermostat is cool, as for example when air is present, and the apparatus is then automatically prevented from becoming air-bound.

A further object is to better protect the differential septum and also permit it to be disabled whenever desired, by a simple manipulation.

Of the accompanying drawings, Figure 1 represents a vertical sectional view of an automatic boiler-feeder provided with my improvements. Fig. 2 represents an enlarged sectional view of the thermostatic valve mechanism.

In the drawings, 10 represents a steam boiler having a normal water-line level at 55 ~~x-x~~ and 11 represents a water-column tube

constituting the main vertical casing of the controller and connected with the boiler 10 above and below the water line by means of pipes 12, 13. The interior of this casing up to a partition 14 constitutes a chamber containing the constant steam pressure of the boiler, and above said partition is a variable-pressure chamber 15 from which a tube 16 extends downwardly to the normal water-line level whereby its lower end is alternately sealed and unsealed by the water fluctuating slightly above and below normal level. 60

17 is the feed-controlling pipe which may be the direct feed-pipe to the boiler, and 18 is a feed-valve in said pipe which may be 70 a direct feed-throttle. The stem 19 of said valve extends through a bearing 20 into the casing of a differential septum or diaphragm 21, the latter having chambers 22 and 23 above and below it.

24 is a pipe leading from the interior of the casing 11 above the water-line to the lower diaphragm-chamber 23 and adapted to contain a column of water which transmits the constant boiler-pressure to chamber 23 so as 80 to act in an upward direction on the diaphragm. 25 is a second pipe connecting the variable-pressure chamber 15 with the upper diaphragm-chamber 22 and adapted to contain a water column which transmits the 85 variable pressure of chamber 15 to diaphragm chamber 22 so as to act in a downward direction on the diaphragm. The pipes 24, 25 contain capacity pots 26, 27 near their upper ends to allow for the movements of the diaphragm without substantial variation of the water heads in said pipes. The water-columns serve to protect the diaphragm 90 from the direct action of steam or of the hottest boiler water. 95

It will be seen that should the water level in the boiler reside below the inlet of tube 16 the steam pressure will have access to both water columns in the respective pipes 24, 25, and the feed-valve 18 will remain open in a depressed position because of its weight and the preponderant water head in pipe 25 acting downwardly like an additional spring or weight. The water-feed, adjusted in excess of the boiler demand, continues until the 100 boiler water rises to cover the inlet of tube 16, whereupon the chamber 15 becomes sealed and any ensuing reduction of pressure caused by condensation or release of the 105 contents of chamber 15 partly relieves the down- 110

ward pressure on diaphragm 22 and the feed-valve 18 tends to close by the preponderance of upward pressure from the boiler transmitted through pipe 24. Boiler water rises 5 in tube 16 as a measure of the differential pressure thus created and also tends to make up the loss of pressure in chamber 15 by rising to take the place of that portion of the steam-pressure which has disappeared by 10 escape or condensation. The body of steam in the chamber 15 and connections acts like a spring which loses some of its elasticity when the tube 16 becomes plugged with water, and the water-plug which rises in 15 said tube acts like a spring-follower, whose weight is subtracted from the total force acting downwardly on the diaphragm, thus giving the differential operating pressure which raises the diaphragm. The height of 20 tube 16 and the length which the water-plug is permitted to assume determines the maximum effective operating pressure which can be attained. Hence it is always desirable to maintain perfect freedom for the movements 25 of the water-plug. Air or other non-condensable gas present with the steam acts like a stiffener for the fluid spring in chamber 15 and connections, whose presence obstructs the rise of the water-plug and retards the 30 condensing action.

In accordance with my present invention I provide a pressure-relief from the variable pressure chamber 15 subject to control by any suitable form of thermostatic device, 35 and I further make the relief-valve adjustable within the limits of this control so that it may either close fully and make the apparatus normally operative by condensation but able to automatically clear itself of air, or the valve may be adjusted to never 40 close entirely but leave at all times a small release which, added to the condensing effect, secures a more rapid reduction of pressure in the chamber 15 when the latter is sealed, or 45 this constant release may on occasion serve as the sole or principal means of pressure reduction as when the pressure fluid is a mixture of steam and fixed gases or composed solely of non-condensable gases. The 50 controller is thereby rendered practically universal in its application to pressure vessels containing a fluctuating liquid and elastic fluid.

A preferred form of my adjustable thermostatically-controlled relief-valve is shown in 55 detail in Fig. 2. 28 is a thermostatic tube with its lower end open to the chamber 15 and its upper end formed with an escape-orifice 29 having a valve seat. The lower 60 end of the tube carries a yoke 30 connected by parallel rods 31 with a second yoke 32, and the upper end of the tube has a guide-plate 33 mounted to slide on the rods. 34 is the needle release-valve whose stem has a 65 boss 35 normally pressed by a spring 36

against the bottom of a hollow thimble 37 constituting a valve adjuster. This adjuster is screwed into the upper yoke 32 and provided with a check-nut 38. The upper end of the valve stem slides freely in a spring adjuster 39 which screws into the valve-adjuster 37 and has a check-nut 40. When the tube 28 is hot from the presence of steam its upper end moves toward the valve 34 and by suitable adjustment of the thimble 37 the 75 valve seat on the tube may be caused to meet the valve and shut off any escape from chamber 15. Pressure reduction in said chamber when water-sealed is then effected normally by condensation of steam and the valve only 80 opens when the tube is very cool, which might be caused by the presence of air or by the clogging of the orifice which would lead in time to the accumulation of air. Any expansion of tube 28 beyond the meeting point 85 of the valve and its seat is accommodated by the spring 36 without producing undue strains. On the other hand, the thimble 37 may be adjusted so that normally, even when hot, the thermostatic tube 28 does not meet 90 the valve 34, and in this case a small release is always provided for the escape of permanent gases which may normally be present in large proportion with steam or may constitute the sole pressure fluid. The amount of 95 opening of the valve will then vary with the temperature of the thermostatic tube which conduces to regularity of operation and tends to dislodge any sediment which may accumulate in the escape orifice.

In addition to the above-named elements I prefer to provide the circulating-pipe 41 leading from the interior of the thermostatic tube 28 to a suitable cold point of the boiler, such as the mud-drum 42. In the absence 105 of this pipe there is a tendency when the boiler is nearly cold or is being started up after standing over night with banked fires, for comparatively cold water to rise in the tube 16 and drip out of the escape orifice 29. 110 This is especially noticeable when the water level has been carried above normal over night as is the usual practice, and the escape of water continues until the hot boiler-water has reached the thermostat and closed the 115 orifice. By the provision of pipe 41 a circulation is provided for the comparatively cold water whereby it may return to the boiler and be replaced by hotter water which will quickly expand the thermostat and thus 120 avoid the drip and the loss of water and heat.

As a measure for disabling the automatic feed-valve 18 and permitting the boiler level to be carried above normal at night (by manipulating a supplementary hand feed-valve 125 or otherwise) and also to allow priming of the pipes 24, 25 in order to keep the water-columns replenished, I provide a by-pass between the pipes 24, 25, consisting of a pipe-loop 43 whose branches are shown as con- 130

nected into the upper and lower diaphragm-chambers 22, 23 and provided with stop-valves 44, 45. Between these valves the bypass loop is connected with a source of water supply. I have shown two such connections, one by means of a pipe 46 tapped into the main feed-pipe 17 and containing a stop-valve 47, and the other by means of a similar pipe 48 leading from some other source of water supply and containing a stop-valve 49.

It is desirable to keep the diaphragm 21 as cool as possible and when the main feed-pipe 17 is connected with a feed-water heater the water columns are preferably replenished from the pipe 48. Otherwise the pipe 46 may be used. To disable the controller, valves 47 and 49 are closed and valves 44 and 45 are opened. The water columns in pipes 24, 25 then tend to equalize at the level of the summit of pipe 24 so long as the boiler level is below the line $x-x$ and the tube 16 unsealed. The feed-valve 18 then descends and remains open by its own weight. It still remains open though the tube 16 becomes sealed for in that case the water rises about equally in tube 16 and pipe 25 and descends in pipe 24.

It will be understood of course that to some extent the features of my invention are capable of use independently of each other though I prefer to use both the thermostatic means and the priming means in conjunction.

I claim:—

1. In a liquid-level regulator, the combination of a variable-pressure chamber having an inlet subject to the liquid level, a differential motor member subject to the pressure in said chamber, an escape outlet from said chamber, and means subject to the temperature in said chamber for automatically controlling said outlet.

2. In a liquid-level regulator, the combination of a variable-pressure chamber having an inlet subject to the liquid level, a differential motor member subject to the pressure in said chamber, an escape outlet from the upper part of said chamber, a valve controlling said outlet, and a thermostat exposed to the interior of said chamber for actuating the valve.

3. In combination, a liquid-level regulator including a differential pressure-actuated motor septum, a variable-pressure chamber associated therewith and having an inlet sealed and unsealed by the fluctuating liquid, an elastic-fluid outlet from said chamber, a

thermostat subject to the temperature in said chamber, a valve controlled by the thermostat and controlling said outlet, and means for independently regulating at will the position of the valve with respect to said outlet.

4. A relief device for differential-pressure regulators comprising a thermostatic tube 65 adapted for connection with the variable-pressure chamber of the regulator and having an escape-outlet at its free end, a support attached to the fixed end of the tube, a valve-adjuster mounted on said support, a valve 70 carried by said adjuster and controlling said outlet, and a spring interposed between said valve and valve-adjuster to permit relative movement between the two after the thermostat has closed the escape-outlet. 75

5. The combination of a steam boiler, a differential feed-controlling motor-member, a variable-pressure chamber associated with said member and having an inlet at the normal water-line level and an escape outlet, 80 a thermostat controlling said outlet and exposed to the temperature of said chamber, and a circulating conduit connecting with the variable-pressure chamber at a point anterior to the escape outlet and returning to 85 the boiler.

6. The combination with a boiler, of a differential feed-controlling septum, a variable-pressure chamber controlled by the water level, water-column pipes connecting with the boiler and with said variable-pressure chamber respectively and leading to opposite sides of the diaphragm, and connections for priming said pipes from a source of water supply external to the boiler. 95

7. The combination with a boiler, of a differential feed-controlling septum, a variable-pressure chamber controlled by the water level, water-column pipes connecting with the boiler and with said variable-pressure chamber respectively and leading to opposite sides of the diaphragm, and priming pipes forming a loop connecting said water-column pipes and having stop-valves and a water-supply pipe connected with said loop 100 and having a stop-valve. 105

In testimony whereof I have hereunto set my hand in the presence of two subscribing witnesses, the 27th day of August 1907.

EDWARD P. NOYES.
